UNITED STATES PATENT OFFICE.

FREDERICK A. SUTPHEN, OF AURORA, ILLINOIS.

COLLAR-BUTTON.

1,150,644.

Specification of Letters Patent.

Patented Aug. 17, 1915.

Application filed October 7, 1913. Serial No. 793,842.

To all whom it may concern:

Be it known that I, FREDERICK A. SUTPHEN, a citizen of the United States, residing at Aurora, in the county of Kane and State of Illinois, have invented certain new and useful Improvements in Collar-Buttons; and I do hereby declare the following to be a full, clear, and exact description of the invention, such as will enable others skilled in the art to which it appertains to make and use the same.

This invention relates to new and useful improvements in collar buttons and has for its object the provision of such a device which is adapted for use in holding the collar in position on the shirt band.

Another object of my invention is the provision of such a device which may be constructed of a single sheet of material, thereby eliminating considerable of the expense entailed in the manufacture of the ordinary collar button.

A further object of my invention is the provision of such a device which will remain in the button hole at all times, thereby preventing loss and other inconveniences occurring in the use of the ordinary type of collar button.

With the above and other objects in view I will now proceed to describe my invention in the following specification and accompanying drawings, in which—

Figure 1 is a sectional view of a collar band and collar showing my improved collar button in place, Fig. 2 is a view of a blank from which my improved collar button is made, Fig. 3 is a rear view of my improved collar button showing same as it would appear in its completed form, and Fig. 4 is a transverse sectional view through the shank of the button.

Referring to drawings by characters of reference, 1 indicates an ordinary shirt having secured thereto the usual neck band 2. This neck band is provided with the usual button hole 3 which is adapted to register with the button hole 4 formed in the collar indicated by the numeral 5.

My improved collar button preferably comprises base 6 having formed integrally therewith and extending laterally therefrom the arms 7. An angularly extending reduced shank 8 is formed integrally with the body portion 6, and is centrally located with relation thereto. This shank is preferably bent upwardly as shown at 9 and thence

back upon itself as indicated by the numeral 10 to form a suitable trough or recess which is adapted to extend transversely through the button holes. The head 11 is extended downwardly and curves inwardly near its lower end as is clearly shown in Fig. 1. Formed laterally of the shank 8 are the ears 12 which are designed to be bent on the dotted lines as shown in Fig. 2 to overlie the shank, thereby increasing the thickness thereof and forming smooth lateral edges thereof which will prevent a button from tearing the ends of a button hole on either the band or collar.

It will be apparent from the foregoing that when it is desired to make use of my improved collar button, the same is inserted in the button hole in the usual manner with the downwardly extending portion 11 on the outside thereof and the lateral extensions 7 lying parallel with the upper and lower edges of the collar band. The collar is then placed on in the usual way and it will be clearly seen that the upper edges of the button holes 3 and 4 will lie in the trough formed between the member 9 and the main body portion 6 thereby preventing said collar from becoming loosened and slipping from its position.

It will be clearly seen that with my improved collar button that the same will stay in its position in the shirt until removed by the user, and also that a collar may be put in place with much less inconvenience and a great saving of time.

While in the foregoing I have shown and described the preferred embodiment of my invention, I wish it to be understood that I may make such changes in the construction, arrangement and combination of parts as will fall within the scope of the claims appended.

What is claimed is:

1. A collar button constructed from a single blank of sheet metal comprising a shank, ears extending laterally from the shank, a base formed on one end of the shank and a head formed on the opposite end of the shank, the base being bent to extend at right angles to the shank, the ears being bent to overlie the shank to increase its thickness and also being designed to prevent wear on the ends of the button hole in which the device is used, the head being bent upwardly in a plane parallel to the base and then back upon itself to form a shoulder, the remain-

ing portion of the head being curved inwardly toward its free terminal.

2. A collar button constructed of a blank of flat metal comprising a relatively broad base, a shank of less width than the base formed centrally of the longitudinal extremities thereof, the shank being formed on one of the lateral edges of the base and being bent to extend at right angles thereto, 10 ears formed on the lateral edges of the shank, said ears being bent back and overlying the shank to increase the thickness thereof and form smooth lateral edges thereon to prevent wear on the collar button hole, 15 a head formed on the end of the shank op-

posite the base, said head being first bent upwardly to extend in a plane parallel to the base and then back upon itself to form a shoulder on the end of the shank and an inwardly curved lower portion at the free end 20 of the head to engage the collar below the button hole and force the lower end thereof inwardly.

In testimony whereof I affix my signature in presence of two witnesses.

FREDERICK A. SUTPHEN.
